MOTORIZED CONVERTER DOLLY

Evan S. Prichard, Newport Beach, Calif., assignor to
Challenge-Cook Bros., Incorporated, Industry, Calif., a
corporation of California

Filed Mar. 16, 1967, Ser. No. 6,250

Term of patent 14 years

(Cl. D14—3)

FIG. 1.

FIG. 2.

FIG. 3.

FIG. 5.

FIG. 6.

FIGURE 1 is an elevation view of the motorized converter dolly of the design of this invention, attached to the conventional trailers which are shown in phantom lines and are included only for illustrative purposes.

FIGURE 2 is a perspective view from above and in front of the motorized dolly converter.

FIGURE 3 is a rear elevation view of the motorized dolly.

FIGURE 4 is a top plan view of the motorized converter dolly.

FIGURE 5 is a side elevation view of the converter dolly taken from the left side.

FIGURE 6 is a front elevation view of the motorized converter dolly.

I claim:

The ornamental design for a motorized converter dolly, as shown and described.
